DRIVING MECHANISM FOR DRILL PRESSES.

Application filed July 6, 1921. Serial No. 482,762.

To all whom it may concern:

Be it known that I, WILLIAM G. ALLEN, a citizen of the United States, residing at Hartford, in the county of Hartford and 5 State of Connecticut, have invented a new and useful Improvement in Driving Mechanism for Drill Presses, of which the following is a specification.

This invention relates to the means employed in drill presses for rotating the tool spindle. In these machines the spindle stands vertically in front and the driving shaft lies horizontally lower down at the back of the frame. On the horizontal shaft 10 is a driving pulley and on the vertical spindle or sleeve through which the spindle extends is the driven pulley, these pulleys being cone pulleys in order that the relative speeds of rotation of the shaft and spindle 15 may be varied. In passing from the driving to the driven pulleys the belt travels around guide pulleys usually mounted on a bracket at the back near the top of the frame. Changing the belt from a pulley step of one 20 diameter to that of another for varying the speed of the spindle necessitates altering the horizontal position of the guide pulleys in order to keep the belt at the proper tension and changing the belt from one step to another 25 step on the spindle or driven pulley requires, in the machines in common use, the raising or lowering of the guide pulleys to the level of the pulley step on which the belt is run. In some prior machines this has 30 been accomplished by raising or lowering the guide pulleys themselves and in other machines by changing the elevation of the bracket that carries the guide pulleys.

The object of the present invention is to 40 eliminate the complicated mechanism employed to raise or lower the guide pulleys themselves and also the expensive and heavy construction necessarily used where the guide pulley bracket is raised and lowered, 45 and provide means which are simple and easy to operate for aligning the spindle pulley with the guide pulleys and giving the belt the proper tension.

This object is attained by arranging means 50 for adjusting the guide pulleys horizontally for insuring the proper tension of the belt, and adjusting the spindle pulley vertically on the spindle sleeve in order that the step used may properly align with the guide 55 pulleys.

In the accompanying drawings, Figure 1 shows a front elevation of the upper portion of a drill press constructed with mechanism that embodies the invention. Fig. 2 shows a side elevation of the same. Fig. 3 shows a top view of the press. Fig. 4 is a vertical section through the spindle pulley, sleeve and supporting head. Fig. 5 is a horizontal section on the plane indicated by the dotted line 5-5 on Fig. 4. Fig. 6 shows an end view of the horizontally movable guide pulley slide and its support. Fig. 7 shows in plan a detail of the means for adjusting the guide pulley slide. Fig. 8 shows in side elevation with a part in section, of a detail of the guide pulley slide adjusting means.

In the drawings only the upper portion of the base 1 of the frame is shown, as the base may have any ordinary design. Mounted on the top of the base is the column 2 of suitable 75 outline. This column at the top and back has an integral bracket 3 and at the front has a yoke-shaped head 4. In the upper and lower ends of the head are anti-friction bearings 5 supporting a sleeve 6 through which passes 80 the tool spindle 7, the tool spindle, as is customary, being connected to the sleeve by a spline so that while rotated by the sleeve it may have an independent vertical movement as raised or lowered by the usual means. 85

Splined on the sleeve so as to drive the sleeve but be capable of independent movement up and down thereon, is a cone pulley 8 having multiple steps. The hub of this pulley rests upon anti-friction bearings 9 90 supported by a yoke 10 that is fastened to the upper end of a vertical bar 11. This bar is guided up and down in a bracket 12 fastened to the head and it is provided with rack teeth 13 that are engaged by a pinion 14 on 95 a horizontal arbor which is carried by a sleeve 15 projecting forwardly from the lower end of the head. On the front end of the arbor is a crank handle 16 and back of the handle and fastened to the sleeve is a 100 disk 17 with stations 18 for stopping the handle in different positions. By turning this handle to the different stations the pinion and rack will raise or lower the pulley so that the desired step of the pulley will 105 align with the guide pulleys 19.

The guide pulleys are mounted in forks 20 swivelled onto a slide 21 that is movable horizontally in ways on the top of the bracket 3. Extending loosely through lugs 110

22 projecting downward from the under side of the slide near one edge is a rod 23. Threaded on the rod outside of the rear lug are adjusting and clamping nuts 24 and 5 thrusting between a nut 25 threaded on the rod and the other lug 22 is a spring 26. This spring normally holds the nuts 24 against the adjacent lug and it has a tension equal to that which it is required of the belt. The 10 front end of the rod 23 is threaded and turning on this thread is a nut 27 bearing a pinion 28 (Fig. 7). Engaging with this pinion is a pinion 29 on the end of a rod 30 that extends forwardly and is supported at 15 the front of the machine by a sleeve 31 fastened to the head. The front end of the rod 30 has a hand wheel 32. By turning this wheel through the rods, pinions, spring and nuts, the slide carrying the guide pulleys 20 may be adjusted horizontally toward or from the spindle pulley. When the tension of the belt reaches that which is desired, the spring yields and the rod 23 moves through the lugs without carrying the slide. The 25 tension of the spring is adjusted to the desired degree by turning the nut 25 up more or less on the rod 23. To prevent more tension being applied to the belt, a latch 33 is pivoted to the under side of the lug at 30 the rear end of the rod 23 adjacent to the nuts 24 and a spring 34 tends to engage the hooked end of this latch with a ratchet toothed rack 35 fixed to the bracket. Under normal conditions the hooked end of the 35 latch is held out of engagement with the rack by the contact of the other end of the latch with the nuts 24 on the rod 23 (Fig. 8), but when the tension of the spring is increased so as to be greater than the desired 40 tension of the belt and the rod 23 moves through the lugs and carries the nuts 24 away from the lug, the latch is free to swing and engage with the rack and hold the slide from further movement in such direction as 45 to tend to increase the belt tension, no matter how much the hand wheel is turned and the spring is compressed.

With this construction the spindle pulley is easily and quickly raised or lowered into 50 exact position to have the belt 36 run around it properly from the tops of the guide pulleys 19 over which the belt passes from the cone pulley 37 on the driving shaft 38 that is supported by a bracket 39 at the 55 top of the base of the frame and that bears a pulley 40 adapted to be connected with a source of power. The guide pulleys are readily adjusted to impart the necessary tension to the belt and when that tension is 60 created the belt cannot be drawn any tighter. The handles for raising and lowering the spindle pulley and for adjusting the guide pulleys are arranged at the front of the machine in convenient position to be 65 reached by the operator.

The invention claimed is:—

1. A driving mechanism for a drill press comprising a rotatable sleeve held from vertical movement at the top in front of the fixed press frame, a cone pulley connected 70 to rotate but to move independently longitudinally on the sleeve, means for moving said pulley longitudinally of the sleeve, guide pulleys mounted on horizontal axes at the back of the top of the press frame, a drive 75 pulley on a horizontal axle mounted at the back of the press frame below the guide pulleys, and a belt passing around the drive pulley over the guide pulleys and around the sleeve pulley. 80

2. A driving mechanism for a drill press comprising a vertical sleeve rotatably supported in bearings fixed vertically at the front of the press frame, a cone pulley movable up and down on, but connected to 85 rotate the sleeve, means for raising and lowering said pulley on the sleeve, guide pulleys mounted on horizontal axes at the back of the top of the press frame, a drive pulley on a horizontal axle mounted on the 90 back of the press frame below the guide pulleys, and a belt passing around the drive pulley over the guide pulleys and around the pulley on the sleeve. 95

3. A driving mechanism for a drill press comprising a rotatable sleeve held from vertical movement at the top in front of the fixed press frame, a cone pulley connected 100 to rotate but move independently longitudinally on the sleeve, means for adjusting 100 said pulley longitudinally on the sleeve, guide pulleys movable horizontally at the back of the top of the press frame, means for adjusting the guide pulleys backward and forward on the press frame, a drive 105 pulley on a horizontal axle mounted at the back of the press frame below the guide pulleys, and a belt passing around the drive pulley over the guide pulleys and around the pulley on the sleeve. 110

4. A driving mechanism for a drill press comprising a rotatable sleeve held from vertical movement with relation to the press frame, a cone pulley connected to rotate but to move independently longitudinally on the 115 sleeve, means for adjusting said pulley longitudinally of the sleeve, swinging guide pulleys mounted on horizontal axes at the top of the back of the press frame, a cone drive pulley on a horizontal shaft mounted 120 at the back of the press frame below the guide pulleys, and a belt passing around the drive pulley over the guide pulleys and around the sleeve pulley. 125

5. A driving mechanism for a drill press 125 comprising a rotatable sleeve held from vertical movement with relation to the press frame, a cone pulley connected to rotate but move independently longitudinally on the tool spindle, elevating mechanism support- 130

- ing said cone pulley, means for operating said elevating mechanism, guide pulleys mounted at the top of the back of the press frame, a drive pulley on a horizontal axle 5 at the back of the press frame below the guide pulleys, and a belt passing around the drive pulley over the guide pulleys and around the pulley on the sleeve.
6. A driving mechanism for a drill press 10 comprising a fixed head, a sleeve rotatably supported by said head, a cone pulley located in said fixed head and connected to rotate but move independently longitudinally on the sleeve, elevating mechanism supporting 15 said cone pulley, means for raising and lowering said elevating mechanism, guide pulleys mounted at the top of the back of the press frame, a drive pulley on a horizontal axle at the back of the press frame below 20 the guide pulleys, and a belt passing around the drive pulley over the guide pulleys and around the sleeve pulley.
7. A driving mechanism for a drill press 25 comprising a rotatable sleeve held from vertical movement with relation to the press frame, a cone pulley connected to rotate but to move independently longitudinally on the tool spindle, means for adjusting said pulley longitudinally of the sleeve, a slide mov- 30 able horizontally on the top of the press frame at the back, means for adjusting said slide horizontally, guide pulleys swivelled upon said slide, a drive pulley mounted on a horizontal axle at the back of the press
- frame below the guide pulleys, and a belt 35 passing around the drive pulley over the guide pulleys and around the pulley on the sleeve.
8. A driving mechanism for a drill press 40 comprising a cone pulley connected to rotate but to move independently longitudinally of the tool spindle, means for moving said pulley longitudinally of the tool spindle, a slide movable horizontally on the top of the press frame at the back, yielding means 45 for moving said slide backward, means for preventing the backward movement of the slide when the tension of said yielding means is overcome, guide pulleys carried upon the slide, a driving pulley mounted on 50 a horizontal axle at the back of the press frame below the guide pulleys, and a belt around the drive pulley over the guide pulleys and around the spindle pulley.
9. A drill press having a fixed head in the 55 front at the top of the frame and a fixed bracket in the back at the top of the frame, a sleeve rotatably mounted in said head, a cone pulley vertically movable in said head on the sleeve, mechanism for raising and 60 lowering said pulley, a slide movable horizontally on said bracket, mechanism for moving said slide toward and from the head, guide pulleys swivelled on said slide, a driv- 65 ing pulley, and a belt passing around the driving pulley over the guide pulleys and around the sleeve pulley.

WILLIAM G. ALLEN.
